UNITED STATES PATENT OFFICE

172,072

ORNAMENTAL CHAIN

Gottlob Armbrust, Edgewood, R. I., assignor to Armbrust Chain Corporation, a corporation of Rhode Island

Application August 14, 1953, Serial No. 26,447

Term of patent 14 years

(Cl. D45—16)

To all whom it may concern:

Be it known that I, Gottlob Armbrust, a citizen of the United States, residing at Edgewood, State of Rhode Island, have invented a new, original, and ornamental Design for an Ornamental Chain, of which the following is a specification, reference being had to the accompanying drawing, forming a part hereof.

In the drawings,

Fig. 1 is a plan view of an ornamental chain embodying my new design; and

Fig. 2 is a side elevational view thereof.

I claim:

The ornamental design for an ornamental chain, as shown.
